FOLDING BRACKET

Ralph W. Swanson, Mt. Pleasant, Mich.

Application October 15, 1935, Serial No. 45,131

1 Claim. (Cl. 287—99)

The present invention relates to new and useful improvements in folding brackets particularly for wall tables or the like and has for its primary object to provide a bracket of this character comprising novel means for locking said bracket in open or operative position.

Other objects of the invention are to provide a folding bracket of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

20 Figure 1 is a view in side elevation of a wall bracket constructed in accordance with the present invention, showing the same in unfolded or operative position.

Figure 2 is a view in front elevation of the invention.

Figure 3 is a vertical sectional view, taken substantially on the line 3—3 of Figure 1.

Figure 4 is a side elevational view, showing the bracket in folded or inoperative position.

30 Figure 5 is a view in cross section through the lock, taken substantially on the line 5—5 of Figure 1.

Figure 6 is a fragmentary view in side elevation, showing the brace as it approaches operative position.

Figure 7 is a perspective view of the upper end portion of the stationary member.

Referring now to the drawings in detail, it will be seen that the embodiment of the present invention which has been illustrated comprises a stationary member 1 of angle iron having a plurality of holes or openings 2 therein for the passage of securing elements for mounting said member 1 on a wall or other support. The stationary member 1 includes a thickened, offset upper end portion 3 having formed therein a step or recess 4.

Pivottally mounted, as at 5, on the portion 3 of the member 1 is a swinging member 6 which is also of angle iron. The member 6 is provided with a plurality of openings (not shown) for the passage of securing elements for mounting a table 7 or the like thereon.

Extending between the free ends of the members 1 and 6 is a brace which is designated gen-

erally by the reference numeral 8, said brace comprising a pair of links or sections 9 and 10 which are pivotally connected, at their outer ends, to said members 1 and 6, as at 11. The inner end portions of the brace sections 9 and 10 overlap and are pivotally connected, as at 12.

The inner end portion of the brace section 9 has formed integrally therewith an angular flange 13 which is engageable with the section 10 in a manner to provide a stop for limiting the swinging movement of the sections 9 and 10 relative to each other toward operative position. Formed integrally with the angular flange 13 is a pair of ears 14 between which a hook or latch 15 is pivotally mounted, said hook or latch being yieldingly urged toward operative or locking position by a spring 16. A portion of one edge of the brace section 10 is substantially beveled or rounded, as at 17, (see Figure 5) in a manner to cause the latch 15 to ride over said member 10 when the bracket is unfolded or opened. To facilitate this movement the hooked end of the latch 15 is substantially beveled or rounded, as at 18. The opposite edge of the section 10 has formed integrally therewith a beveled lip 19 with which the latch 15 is engageable for releasably locking the brace 8 in unfolded position.

It is thought that the operation of the bracket will be readily apparent from a consideration of the foregoing. To open the bracket, the member 6 is, of course, swung upwardly to a position substantially at right angles to the member 1, thus unfolding the brace 8. When the sections 9 and 10 of the brace 8 reach substantially the position shown in Figure 6 of the drawings, the latch 15 engages the beveled portion 17 of the section 10 and rides thereover. Then, when the brace 8 reaches substantially its unfolded position the latch 15, under impulsion by the spring 16, engages under the beveled lip 19 and the bracket is thus positively locked in open position. To fold the bracket it is only necessary to disengage the latch 15 from the beveled lip 19 against the tension of the spring 16, after which the sections 9 and 10 may be "broken" or swung inwardly for permitting the member 6 to swing downwardly to the position shown in Figure 4 of the drawings. The thickened portion 3 of the stationary member 1 materially strengthens or reinforces the bracket at a point which is usually subjected to severe strain.

It is believed that the many advantages of a folding bracket constructed in accordance with the present invention will be readily understood, and although a preferred embodiment of the de-

vice is as illustrated and described, it is to be understood that changes in the details of construction and in the combination and arrangement of parts may be resorted to which will fall within the scope of the invention as claimed.

5 What is claimed is:—

A brace including a pair of sections pivotally connected at one end and, when unfolded, extending in overlapping relation to each other, a bevelled lip on the inner end portion of one of the

sections, an angular flange on the inner end portion of the other of said sections, said angular flange being engageable with said one section for limiting the movement of the sections toward unfolded position, ears projecting from the flange, 5 and a spring actuated latch pivotally mounted between the ears and operatively engageable with the bevelled lip for releasably locking the sections in unfolded position.

RALPH W. SWANSON. 10
